United States Patent

Des. 235,882
Patented July 15, 1975

235,882

LIGHTER

Franz Alban Stuetzer, Muhlheim am Main, Germany,
assignor to Rowenta-Werke, G.m.b.H.

Filed May 7, 1974, Ser. No. 467,704

Claims priority, application Germany, Nov. 9, 1973

Term of patent 14 years

Int. Cl. D2—05

U.S. CL. D27—42

FIG. 1 is a perspective view of a lighter showing my new design including the top, front, and one side thereof, the other side being substantially a mirror image of the side shown;

FIG. 2 is a front elevational view thereof;

FIG. 3 is a rear elevational view thereof;

FIG. 4 is a top plan view thereof; and

FIG. 5 is a bottom plan view thereof.

I claim:

The ornamental design for a lighter, as shown and described.
